UNITED STATES PATENT OFFICE.

GEORGE WESTINGHOUSE, OF PITTSBURGH, PENNSYLVANIA, ASSIGNOR TO THE WESTINGHOUSE AIR BRAKE COMPANY, OF PITTSBURGH, PENNSYLVANIA, A CORPORATION OF PENNSYLVANIA.

DRAFT-GEAR.

1,120,005.

Specification of Letters Patent.

Patented Dec. 8, 1914.

Application filed April 12, 1906. Serial No. 311,284.

To all whom it may concern:

Be it known that I, GEORGE WESTINGHOUSE, a citizen of the United States, residing in Pittsburgh, in the county of Allegheny and State of Pennsylvania, have invented certain new and useful Improvements in Draft-Gear, of which the following is a specification.

This invention relates to railway draft appliances for cars and other rolling stock, and appertains more particularly to an automatic coupler head and a yielding resistance mechanism for connecting a coupler head to the draft timbers or frame-work of the car body or truck.

One of the principal objects of my invention is to provide an improved yielding resistance connection between the coupler head and the car, which mechanism will also be laterally flexible to permit a limited transverse or swinging movement of the coupler or draw bar. This feature of my invention preferably comprises a coiled spring mechanism, one end of which is connected to the draw bar or coupler, while the other end, or another portion of said spring, is securely held by a connection to the car or framework, whereby the draft and buffing strains will subject the spring alternately to tension and compression, or vice-versa, and the end of the spring at which the draw bar or coupler is attached will be capable of a limited lateral movement, due to the flexibility and elasticity of the spring.

Another object of my invention is to provide an improved and simple means for attaching the spring to the coupler head or draw bar or to the casing by forming a groove adapted to fit the spring, upon or in the part to which the spring is to be attached and then screwing the coiled spring into the groove.

Another object is to provide an improved spring supporting casing adapted to be secured to the draft timbers or framing of the car and having a split end portion for clamping the spring and an outwardly flaring portion for permitting a lateral bending movement of the free end of the spring.

Another object is to provide yielding means for normally deflecting the coupler head slightly to one side of the center line of the car for the purpose of insuring the proper engagement of the coupler heads

with each other to effect the automatic coupling of cars upon a curved track.

Another object is to increase the capacity of the spring gear by means of a friction spring having one or more coils mounted between adjacent coils of the draft spring and provided with frictional engaging surfaces.

In the accompanying drawings, Figure 1 is a vertical longitudinal section of a spring draft gear embodying some of my improvements; Fig. 2 a similar sectional view showing a modification, in which friction springs are employed having coils located between adjacent coils of the draft spring; Fig. 3 a central horizontal section of the gear with my improved automatic coupler and tubular draw-bar; Fig. 4 a horizontal section of a modified construction in which the spring is secured in a trunnion pivoted in the fixed casing, and also showing a different form of connection between the spring and the coupler head; Fig. 5 a vertical section through the casing and trunnion, and showing a portion of the spring secured therein; Fig. 6 a transverse section through the casing, the trunnion being indicated in elevation; and Fig. 7 a horizontal section of a construction embodying features shown in Figs. 2 and 4.

According to the construction shown in Fig. 1, the improved spring gear comprises a single helical spring securely supported at a central or intermediate portion by a casing 11, which may be connected to the draft timbers or members of the car or truck frame, and forming thereby two spring sections, an outwardly extending section 10 and an inwardly extending section 9. Owing to the elasticity of the spring these ends of the spring sections have a certain lateral flexibility which permits a limited transverse movement of the coupler or end of the draw bar to which these spring sections may be connected in any desired manner.

According to the construction shown in Fig. 3, the draw bar 16 extends longitudinally through the coil of the spring and is provided at one end with a head 14, in which is formed a helical groove 18, adapted to fit the pitch of the spring and to be screwed into the end of the outer helical spring section, while a block 15, provided with a similar groove, is mounted on the inner end of the draw-bar. In a similar manner, the block 15 is screwed into the inner

end of the helical spring section 9 and is firmly held against the shoulder 17 on the bar 16 by means of a washer 19 and nuts 20. In this way the draw-bar is securely attached to the opposite ends of the helical spring sections by a simple and durable form of connection, which may be readily detached and replaced when necessary.

Any suitable form of casing for supporting the spring may be employed, but, as shown, this casing 11 comprises a split end portion 13 having formed in the inner surface thereof a helical groove, into which the spring is adapted to be screwed, and bolts 12 for clamping the same when properly adjusted. The casing also has an outwardly flaring portion surrounding the spring section 10 for permitting a certain lateral play of the coupler, and may also be provided with flanges 22, as indicated in Fig. 3, for securing the same to the car frame.

As shown in Figs. 1 and 2, a standard Master Car Builders' coupler head 21 may be attached in any suitable manner to the draw-bar. It will now be seen that considerable flexibility of action may be obtained with this form of construction, since the coupler is flexibly supported at the free ends of the spring sections and may be deflected by pressure either vertically or laterally throughout a limited range of movement. Either draft or buffing strains will be transmitted through both sections of the spring, subjecting one section to compression and the other section to tension, thereby securing double spring capacity. This spring capacity may be increased, if desired, by the addition of friction springs 23 and 24, as shown in Fig. 2, the coils of which are mounted between the coils of the draft spring sections 10 and 9, and are provided with frictional surfaces adapted to engage the surfaces of the coils of the draft spring when the latter is subject to compression.

According to the construction shown in Fig. 3, the spring gear is substantially the same as that shown in Fig. 1, except that the drawbar is tubular, having a passage 25 extending therethrough and connected at its outer end to my improved form of automatic coupler head 30, which is covered in my divisional application hereinafter referred to, having a registering passage 34 leading to the gasket opening 33 in the face of the coupler for coupling a fluid pressure conduit, such as a compressed air line, through the train, a hose 26 being connected at the inner end of the draw-bar.

The automatic coupler head 30 is similar in some respects to that covered by my prior patent, No. 708,747, of Sept. 9, 1902, comprising a forward projecting portion 31 on one side and a recessed portion on the other side adapted to engage a corresponding recess and projection of a counterpart cou-

pling on an adjacent car when the two are coupled together, the longitudinal face of the coupling being provided with vertical ribs 35 having inclined sides for locking against corresponding ribs on the other half 70 of the coupler. A latch or locking lever 38 is pivoted on a vertical shaft 37 and is normally pressed outward by a spring 39 for engaging a suitable bearing surface on the outer side of the projecting portion 31 of 75 a counterpart coupler after the vertical rib portions 35 have slipped past each other and thereby firmly lock the two coupler heads together, all as fully set forth in my prior patent above referred to.

The head 14 of the draw-bar may be screwed into the shank of the coupler head, as shown in Fig. 3, and in order to provide a tight joint for the fluid pressure conduit at this point a gasket 27 may be mounted 80 in the head of the bar and bear against the coupler around the opening of passage 34 when the parts are tightly screwed together and clamped by suitable means, such as a set screw 40. A ring 41 may be forced onto 85 the shank of the coupler to prevent any tendency of the threaded parts of the coupler to spread at this point.

Referring again to Fig. 3, it will be noticed that the coiled spring sections 9 and 10 are so arranged in the fixed casing that the axis of the spring and coupler head, indicated by the dotted line $x-x$, makes an angle with the center line of the car, indicated by the dotted line $y-y$, so that the 95 coupler head is normally deflected a slight distance to one side of the center line of the car. This is for the purpose of facilitating the coupling of cars upon a curved track and to insure the engagement of the 100 pointed projection 31 of one coupler head with the counterpart coupler head on the gathering hood side of its corresponding projection. If the coupler heads were normally located on the center lines of the cars, 105 it might happen that in an attempt to couple cars together on a curved track the projecting portions 31 of two coupler heads would engage each other upon their outer sides and thus fail to couple together automatically, 110 but this cannot occur where the coupler heads are normally deflected sufficiently to one side of the center line, as illustrated in the drawing. After the two members are coupled together, and the draft stresses are 115 applied the springs readily flex laterally, so that the axis and line of draft then coincide with the center line of the car.

If it should be desired to employ a very light resistance spring for normally deflecting the coupler laterally, a structure such as shown in Figs. 4, 5 and 6 may be used, in which the draft spring is mounted in a trunnion piece 51, which is pivotally secured 120 in the fixed casing 11. According to this 125

construction the casing is formed in two parts adapted to be secured together by bolts in flanges 22' and the trunnion 51 is mounted to have a slight turning movement upon a vertical pivot in said casing. After the spring is screwed into the trunnion, it may be rigidly held therein by a clamping piece 52 and set screw 53. A light spring 54 bears upon the side of the trunnion and normally deflects the coupler head to one side, as indicated by the angle between the dotted lines $x-x$ and $y-y$.

When the members are coupled together and draft stresses applied, the light resistance spring 54 readily yields, so that the line of draft coincides with the center line of the car.

In Fig. 4 I have also shown a modified form of connection between the draft spring and coupler head. The rear end or shank of the two members or halves 28 and 29 of the coupler is provided with a recess for receiving a flange 57 on the end of the tubular bar 16, and has slightly tapered end 55 on which is formed a substantially helical groove for receiving the slightly flared end of the coiled spring 10. In this way, the end coils of the spring also serve as means for holding the two parts 28 and 29 of the coupler securely clamped together over the flanged end of the tubular bar 16.

While I have herein fully described and shown certain features of my improvements relating to a combined train air-brake pipe and car coupling mechanism, this is not expressly claimed in this application since the same forms the subject matter of a divisional application, Serial No. 434,450, filed May 23, 1908.

Having now described my invention, what I claim as new, and desire to secure by Letters Patent, is:—

1. A draft gear comprising a helical spring formed of an outwardly extending section and an inwardly extending section, a casing securely holding the spring at a point between said sections and connected to the car frame, and a draw-bar extending through the coil and connected to the free ends of the spring sections. 50

2. A draft gear comprising a helical spring, a flaring casing connected to the car frame and having a split end for clamping the spring, and a draw bar connected to a free end of said spring. 55

In testimony whereof I have hereunto set my hand.

GEO. WESTINGHOUSE.
